(57) CLAIM

The ornamental designs for a candle or oil lamp having a planar or bent planar wick, as shown and described.

DESCRIPTION

FIG. 1 is a perspective view of a first embodiment of the candle or oil lamp having a planar or bent planar wick;
 FIG. 2 is a perspective view of a second embodiment of the candle or oil lamp having a planar or bent planar wick;
 FIG. 3 is top plan view thereof of the first and second embodiments of the candle or oil lamp having a planar or bent planar wick;
 FIG. 4 is a side perspective view of the first embodiment of the candle or oil lamp having a planar or bent planar wick;
 FIG. 5 is a side perspective view of the second embodiment of the candle or oil lamp having a planar or bent planar wick;
 FIG. 6 is a perspective view of a third embodiment of the candle or oil lamp having a planar or bent planar wick;
 FIG. 7 is a perspective view of a fourth embodiment of the candle or oil lamp having a planar or bent planar wick;
 FIG. 8 is top plan view thereof of the third and fourth embodiments of the candle or oil lamp having a planar or bent planar wick;
 FIG. 9 is a side perspective view of the third embodiment of the candle or oil lamp having a planar or bent planar wick;
 FIG. 10 is a side perspective view of the fourth embodiment of the candle or oil lamp having a planar or bent planar wick;
 FIG. 11 is a perspective view of a fifth embodiment of the candle or oil lamp having a planar or bent planar wick;
 FIG. 12 is a perspective view of a sixth embodiment of the candle or oil lamp having a planar or bent planar wick;
